[57] CLAIM

The ornamental design for a reflector assembly, as shown and described.

DESCRIPTION

FIG. 1 is a perspective view of one side and top of the reflector assembly showing my new design;

FIG. 2 is a perspective view of the bottom and other side of the reflector assembly shown in FIG. 1;

FIG. 3 is a cross-sectional view of FIG. 1 taken along the line 3—3;

FIG. 4 is a top view of FIG. 1; and

FIG. 5 is an exploded view of the reflector assembly shown in FIG. 1.

FIG. 1

FIG. 4

FIG. 2

FIG. 3

FIG. 5
